BRUSH CONSTRUCTION AND MOUNTING
THEREFORDietrich F. O. Wesemeyer, Euclid, Ohio, assignor
to Spiral Brushes, Incorporated, Cleveland,
Ohio, a corporation of Ohio

Application September 12, 1942, Serial No. 458,163

8 Claims. (Cl. 15—182)

This invention, as indicated, relates to a brush construction and mounting therefor. More particularly, it comprises a brush unit formed as a coil or spiral type, and preferably has the end faces thereof brought into parallelism with each other. The invention also includes the formation of spiral brush units adapted to be assembled on a sleeve, mandrel or other type of support, and held firmly upon such support for rotation against the work. It also includes a brush construction wherein the active brush elements may be renewed from time to time or replaced with units of lesser or greater width, as may be required for certain types of work, so that work of great width can be operated on when required, or the brush area reduced in proportion to work of lesser width so that needless waste of brush material will be avoided.

The principal object of the present invention is to provide cylindrical brush units preferably formed of spirally wound type and mountings therefor permitting adaptability of such unit for work of various types and ready replacement of parts subjected to wear.

Another object of the invention is to provide a brush construction of low cost and high efficiency adapted for industrial use under severe service conditions, and having features permitting easy installation and replacement.

Another object of the invention is to provide a spiral brush construction having flat parallel end faces and securely engaged upon a sleeve in a manner permitting rapid construction at low cost.

Another object of the invention is to provide a spiral brush construction, the ends of which are formed into rings of predetermined size and the intermediate portions of which are held in firmly pressed relation to each other so that brushing operations may be carried on at high speed and with uniformity of action upon the material operated on.

Another object of the invention is to provide spiral brush units with mounting sleeves firmly connected therewith, such sleeves being adapted for interlocking engagement with each other and with the supporting drive shafts on which they are mounted.

Other and further objects of the invention will appear in the course of the following description.

To the accomplishment of the foregoing and related ends, said invention, then, consists of the means hereinafter fully described and particularly pointed out in the claims, the annexed drawings and the following description setting forth in detail certain structures embodying the invention, such disclosed means constituting, however,

but several of various forms in which the principle of the invention may be used.

In the said annexed drawings:

Fig. 1 is a side elevation, broken away in part, of a brush construction embodying the features of the invention, and showing a central vertical section adjacent one end, as seen along the line 1—1 shown in Figure 2;

Fig. 2 is an end view of the structure shown in Figure 1;

Fig. 3 is a side elevation, partly in section, showing a brush construction along the lines of the unit shown in Figures 1 and 2 and mounted on a polygonal shaft in clamping relation thereto so as to provide a unit for high speed operation;

Fig. 4 is a sectional detail view of the polygonal shaft and the engaging portion of the brush structure as seen along the line 4—4 shown in Figure 3 looking in the direction of the arrows;

Fig. 5 is a side elevation, partly in section, showing the internal and external construction of a brush holding sleeve provided with inwardly displaced areas forming internal lugs in the sleeve for engagement with an hexagonal shaft;

Fig. 6 is an end view of the structure shown in Figure 5 showing the lug members at the ends of the sleeve in outwardly turned or locking position;

Fig. 7 is a fragmentary view of one of the inwardly displaced areas of the sleeve providing internal lug members as seen along the line 7—7 shown in Figure 5 looking in the direction of the arrows;

Fig. 8 is an end view of a sleeve formed with inwardly displaced areas so positioned as to engage over a shaft of square cross-section;

Fig. 9 is a view similar to Figure 8 showing the sleeve as provided with inwardly displaced areas adapted to fit upon the shaft octagonal in cross-section;

Fig. 10 is a fragmentary sectional view showing a brush construction adapted to be fitted upon a sleeve or shaft by means of holding lug members engageable with the support and with the marginal areas of the brush structure adjacent the respective ends thereof;

Fig. 11 is an end view of the structure shown in Figure 10, the brush structure shown in said figures being of the buffer type;

Fig. 12 is a fragmentary detail view showing a modified type of locking tab adapted to hold a brush unit upon a sleeve;

Fig. 13 is a fragmentary view showing another form of modified locking tab adapted to hold a brush on a sleeve or similar member;

Fig. 14 is a perspective view illustrating the

manner of folding or twisting a buffer strand and stitching the same to provide material for a buffering brush for heavy duty service:

Figures 15 and 16 are fragmentary perspective views showing respectively, terminal and intermediate clamping claw plates adapted to be placed on opposite sides of a tubular support to firmly hold the spiral brush unit in engagement therewith.

Fig. 17 is a side elevation, partly in section, 10 wherein combined supporting sleeve sections having clamping claw flanges are provided to support replaceable brush units; and

Fig. 18 is a side elevation, partly in section, 15 showing a replaceable brush unit mounted on a supporting sleeve unit provided with a clamping claw flange, and a clamping ring provided with claw elements and providing a transferable unit for engagement on a drive shaft.

The various figures of the drawings all relate 20 to brushing units of the coil or spiral type and the mountings therefor, wherein economy of operation may be obtained through assembling the brush units in widths proportioned to the widths of the work to be operated on and also in providing for the ready replacement of brushing units upon the operating shaft or mandrel so that a minimum of time is required for replacement in continuous industrial operations.

The construction illustrated is adapted for narrow width, high speed, brushing units formed of wire of special characteristics for the work in hand, and also for units of specifically greater width, including those of extremely wide width for certain scrubbing or finishing operations at 35 somewhat slower speeds than the brushes of narrow width. In each instance the brushing units are provided with clamping means to insure the coils being of suitable sizes to engage the shafts or mandrels upon which they are to be mounted.

As is clearly shown in Figures 1 to 6, inclusive, the invention comprises a brush unit 1 formed of a channel strip 2 having brushing elements 3 engaged about a holding wire 4 and wound into spiral form providing shaped areas 5 displaced 45 transversely so as to form flat end faces 6 at each end of the brush unit. The unit above described is preferably engaged upon a hollow sleeve 7 of light metal formed with a plurality of retaining tabs 8 and 9 at the respective marginal end portions thereof, said respective tabs, at the opposite ends, being positioned in alternately spaced relation about the circumference of the sleeve as related to their companion lugs on the opposite end. When the brush unit is placed upon the sleeve the tabs are bent outwardly at right angles to their original position and serve to lock the unit firmly upon the sleeve, having securing pins 10. In order to have the sleeve interlockingly engage a shaft of rectangular cross-section, shown as an hexagonal shaft 11 in Figure 3, the sleeve is provided with a plurality of inwardly displaced areas 12 at suitably spaced points around the circumference of the sleeve so as to present an internal arrangement of lugs combining to form an hexagonal area within the sleeve or locking arrangement with the shaft.

The depressed areas 12, as shown in Figure 7 form the locking lugs on the internal surface of the sleeve, and said depressions are preferably turned at a slight angle so as to provide greater interlocking capacity on the part of the sleeve when engaged upon the shaft.

The position of the lugs will be changed in accordance with the cross-section of the shaft to be

engaged. Where a sleeve is to engage a square shaft the lugs 13, preferably four in number, are positioned in staggered relation around the sleeve presenting a rectangular central opening, as shown in Figure 8. Another polygonal form of interlocking arrangement is shown in Figure 9 wherein the lugs 14 are likewise staggered in space and slightly inclined around the sleeve so as to provide an opening of octagonal outline to engage upon an octagonal shaft. In order to permit a manufacturer to replace a new unit for brushing purposes upon a sleeve carrying a worn out brush, the sleeve may be formed as shown in Figures 10 to 13 wherein demountable holding tabs 15 are utilized to hold the brushing unit upon the sleeve in the form illustrated in Figures 10 and 11. The holding tab comprises an elongated member bent upwardly at its outer end and downwardly at its inner end. A secure anchorage of the tab to the channels holding the brush unit may be obtained by forcing a steel pin 16 through the outer marginal area of the tab and through the adjacent upper margins of the coils of the channel member 17. In place of using a demountable tab of the type shown in Figure 10, the tab 18 may be formed as shown in Figure 12 wherein a hook member 19 is provided, said member engaging through an elongated slot 20 in the sleeve, being forced outwardly into locking engagement with a reduced portion of the sleeve 21 at the bottom of a channel 22 within which the tab is slidably engaged. When the brush unit is in position upon the sleeve just described it may be mounted upon a shaft by means of a beveled clamping member 23 engaging the end thereof, the sleeve preferably having a beveled end portion 24 to cooperate with the beveled surface of the clamping member. The demountable tab 25 shown in Figure 13 is formed with a hook member 26 and is substantially the same shape as the demountable tab 18 shown in Figure 12. It is mounted on a sleeve 27 of heavier gauge and the hook portion thereof does not project below the inner surface of the sleeve by reason of a channel 28 being provided on the under side of the sleeve at the point where a channel 29 is provided on the upper side thereof to receive the demountable holding tab. The hook member is engaged through an elongated slot 30 formed in the sleeve in spaced relation to the end portion thereof.

When the brush unit is engaged upon a sleeve of the character shown in Figures 10 to 13, inclusive, the tab members at one end may be pre-formed so as to be positioned at right angles to the axis of the sleeve, and the remaining tabs may be struck up into clamping position as soon as the brush unit is mounted upon the sleeve. When the brush becomes worn and has to be discarded the struck up portions of the tabs of the unit may be forcibly displaced from clamping relation and a new unit substituted with a new series of demountable tabs to hold the substituted brush unit in position upon the sleeve. The unit whether formed with integral tabs as shown in Figures 1, 2, 3, 5 and 6, or whether formed with tabs as shown in Figures 10, 11, 12 and 13, is preferably held in clamping relation upon a shaft by means of recessed end washers 31 securely clamped into position by means of clamping nuts 32. The shaft 11, shown in Figure 3, is of hexagonal outline, and the sleeve has the inwardly displaced lugs 12 adapted to engage the respective surfaces of the hexagonal area of the shaft. A screw threaded portion of the shaft at each end permits

the clamping nuts 32 to be firmly held against the recessed washers 31, which, as shown in Figure 3, overlap the end portions of the channel strip 2 at the respective ends of the brush unit. In order to provide a high speed buffer unit for heavy duty service, I form the strands 33 in the manner shown in Figures 10, 11 and 14, wherein strips of muslin, or similar suitable buffing fabric, are turned in at each marginal edge toward each other and folded several times, shown as three in number in Figure 14. The strands with the folded marginal areas are then twisted to one side or the other, shown as twisted in counter-clockwise direction in Figure 14, and are then held in such position by means of a lock stitch seam providing marginal stitches 34, as shown more particularly in Figure 14.

When roller brushes of extended width are used, particularly those mounted on a tubular sleeve and formed as a single unit extending the full width of the work it is practical to secure such single unit on the tubular support by means of claw clamps of the character illustrated in Figures 15 and 16. The tubular support is usually of considerably greater length than the width of the work, and provides free end areas to which the clamping claws may be secured.

The supporting tubular shaft is then mounted on the driving shaft in any preferred manner, such as by means of beveled clamping members of the type illustrated in Figure 12 of the drawings. The brushing units referred to are usually formed of Tampico, or of buffer material, and are rotated at much slower speed than the narrow wire brushes used for removing scale and the like. The tubular support 41 is preferably provided adjacent each end with one or more apertures 42 which may be counter-sunk at their inner ends to receive a bolt 43 which engages through a central aperture in the terminal claw plate 44, as shown in Figure 15, or in an intermediate claw plate 45, as shown in Figure 16. It is to be understood that where a roll type spiral brush unit 46 is to be secured on a tubular support 41 the spiral unit is slidingly engaged upon the tubular support, and the end portion of the spiral unit is engaged by the terminal claw plate 44 in the manner disclosed in Figure 15. The claw plate is secured by means of the bolt 43 extending upwardly through an aperture in the tubular support and is firmly held in position by means of a nut 47. The base of the claw plate is preferably curved upon a radius identical with that of the tubular support, and adjacent the channel strip 48 is provided with a number of claws for engaging said channel strip. The claws shown in Figure 15 are three in number, two of the claws 51 being of a height sufficient to permit their gripping terminals to bear against the upper edge of the channel strip intermediate the tufts of brushing material clamped therein. The brush structure is formed in the manner heretofore described and has a holding wire 53 centrally of the channel strip. In the form illustrated in Figure 15 the holding wire is bent upon itself so as to enter a depression 54 formed in the adjacent claw member 55. The terminal portion 56 of the claw member bears against the end portions of the channel strip, the claw thus serving to hold the brushing unit against movement toward the right by reason of the engagement of the holding wire with the claw 56, or to the left by reason of its engagement with the extreme end of the channel strip. A claw member of identical construction with the claw member shown in Figure 75

15 is used at the longitudinally opposite end of the roller brushing unit to similarly engage a clamp with the free end of the channel strip at such point.

5 The companion clamping units, or claw plates, for the two terminal units just mentioned are formed with a series of claws 57, shown as three in number, each of said claws having their terminal portions 58 engaged over the top edge of the channel strip 48. The intermediate claw plates 45 are of substantially the same construction as to their body portions as the claw plates 44 heretofore described, and are held in position by a bolt 59 and nut 60 extending through an aperture in the tubular member 41 at a point preferably diametrically opposite the terminal claw plates heretofore described. If desired, several intermediate claw plates may be placed about the tubular support member to insure the particular engagement of the end portions of the roller brush structure with the tubular support.

20 The claw type of clamping means just described permits brushing and polishing operations to be carried on very efficiently at a minimum of cost.

25 The brushing units are readily detachable from the tubular supports, and the tubular supports themselves are readily detachable from the driving shaft. As soon as a brush becomes worn, or in need of trimming, it may be easily removed 30 and replaced by a brush suited to the work in hand. It is desirable to employ a brush of practically the width of the work to be finished in order that the wearing down of the strands or fibres of the brushing unit may be distributed 35 evenly about the entire active surface of the brushing unit.

The use of claw clamping units may also take various forms wherein an enlarged hub for the brushing unit is provided where brushes are to be

40 engaged upon shafts of relatively small diameter. In the type of structure illustrated in Figure 17 the clamping of the unit upon the shaft is accomplished through the use of two sleeve members 61, 62, the sleeve member 61 bearing against a shoulder 63 on the drive shaft 64. The sleeve members may be made of cast metal or the like and provided internally with hollow areas 65 in order to make them of less weight. Each sleeve member is provided with an upstanding flange 66 with internally projecting teeth or claw members 67. The outer sleeve section 62 is preferably provided with a central hub or extension 68 against which a locking ring 69 may be brought into pressure relation. The locking ring is internally screw-threaded to engage a screw-threaded area 71 on the shaft and may be operated by a spanner wrench engaging in the recesses 72 provided therefor about the periphery of said ring.

45 The replaceable brush units 73 engaged within the sleeve section just mentioned are preferably made of a width slightly greater than the width of the two sleeve sections when brought into abutting relation with each other, thus allowing an intermediate space or area 74 between the two sleeve sections to permit a certain degree of clamping pressure to be brought directly against the coils of the replaceable brush unit and hold the same firmly clamped against each other.

50 In the construction shown in Figure 18 the mounting of the replaceable brushing unit may take place in approximately the manner described in connection with the structure shown in Figure 17, or the mounting of the replaceable coil upon the supporting sleeve may be carried out

before the sleeve and clamping brush unit are placed upon the drive shaft. As is clearly shown, an inner cylindrical sleeve 75 is engaged directly upon the shaft 76 against a shoulder 77 and is held in clamping relation upon said drive shaft by means of a nut 78 screw-threadedly engaged upon a screw-threaded portion 79 of the drive shaft. The inner cylindrical sleeve 75 is connected with an outer supporting sleeve 81 by means of annular discs 82, 83, secured adjacent 10 the respective ends of said sleeves by welding or similar securing means. The outer sleeve is provided adjacent its inner margin close to the plane of the shoulder of the drive shaft with a flange member 84 of annular shape welded to the outer sleeve; said flange member being provided with a plurality of inwardly projecting teeth or claws 85 adapted to project within the brush material of the replaceable brush unit and hold the same in clamping relation to the sleeve. At the end of the outer sleeve opposite the flange 84 just described an annular clamping ring 86, corresponding in function with the fixed flange 84, is provided having inwardly projecting teeth or claws 87 engaging the brush material in the manner of the teeth 85 heretofore described. The outer sleeve is provided with a series of key-ways 88 within which inwardly projecting lugs 89 on the annular clamping ring 86 are engaged. The clamping ring 86 is forced inwardly into clamping relation with the adjacent coils of the replaceable brush unit by means of a locking ring 91 which may be operated by a spanner wrench engaging the recesses 92 about the periphery of said ring.

The key-ways 88 heretofore mentioned are preferably formed completely across the face of the outer sleeve at suitably spaced intervals and may serve to lock a ring flange against rotation as set forth. The end portions of the flange 84 and the ring member 86 may be suitably recessed at such points to conform to the end faces of the replaceable units when the same are constructed with end faces not pressed into parallel relation with each other. In place of providing recesses in the flanges 84, 86, respectively, suitably conformed washers to bear against such elements may be utilized, such washers compensating for irregularities in the end faces of the replaceable units.

The invention in its various forms provides a basis for the wide use of brushing apparatus in conditioning and finishing different articles of manufacture. When other means are resorted to, such as sand-blasting and the like, there is often a destructive effect on the surface and a wastage of material. The surface appearance is enhanced through brushing operations and a smooth finish is often essential for the use for which an article is fabricated. With a wide selection of replaceable brushing units available at low cost, the advantages of this type of production facility are open to a much larger field of use than has heretofore been the practice.

Other modes of applying the principle of my invention may be employed instead of those explained; change being made as regards the structure herein disclosed, provided the means stated by any of the following claims or the equivalent of such stated means be employed.

I therefore particularly point out and distinctly claim as my invention:

1. An apparatus of the character described having in combination, a brushing unit formed of a channel strip carrying brushing strands

wound to spiral form, a tubular supporting member engaged within said unit and a plurality of spaced projections carried by the respective ends of said tubular member bearing against the end faces respectively, of said brushing unit over the full height and over the top edge of the channel strip thereof, and means for mounting said tubular member upon a driving shaft.

2. An apparatus of the character described having in combination, a brushing unit formed of a channel strip carrying brushing strands wound to spiral form, a tubular supporting member engaged within said unit and a plurality of spaced projections carried by the respective ends of said tubular member bearing against the end faces respectively, of said brushing unit over the full height and over the top edge of the channel strip thereof, and intermediate the marginal brushing strands, and means for mounting said tubular member upon a driving shaft.

3. An apparatus of the character described having in combination, a brushing unit formed of a channel strip carrying brushing strands and wound to spiral form, a tubular supporting member engaged within said unit by means of a plurality of spaced projections bearing against the end faces thereof in the form of integral tabs in alternately spaced relation formed at opposite ends of said tubular supporting member and bent upwardly and inwardly into clamping engagement with the channel strip of said brushing unit.

4. An apparatus of the character described having in combination, a brushing unit formed of a channel strip carrying brushing strands and wound to spiral form, a tubular supporting member engaged within said unit by means of a plurality of spaced projections bearing against the end faces thereof in the form of integral tabs in alternately spaced relation at opposite ends of said supporting member and bent upwardly and inwardly into clamping engagement with the channel strip of said brushing unit, and a plurality of angularly positioned ribs formed internally of said tubular member, said ribs being distributed about the inner circumference of said tubular member so as to provide cooperative interlocking members to engage upon a shaft of polygonal cross-section.

5. An apparatus of the character described having in combination, a brushing unit formed of a channel strip carrying brushing strands and wound to spiral form, a tubular supporting member engaged within said unit by means of a plurality of spaced projections bearing against the end faces thereof in the form of integral tabs in alternately spaced relation at opposite ends of said supporting member and bent upwardly and inwardly into clamping engagement with the channel strip of said brushing unit, a plurality of angularly positioned ribs formed internally of said tubular member, said ribs being distributed about the inner circumference of said tubular member so as to provide cooperative interlocking members to engage upon a shaft of polygonal cross-section, and a securing pin engaged through at least one of said upturned tabs and through the adjacent channel strip to provide a permanent anchorage for the end portion of said brushing unit.

6. An apparatus of the character described having in combination, a brushing unit formed of a channel strip carrying brushing strands engaged around a holding wire within said channel strip and wound to spiral form, at least one supporting member engaged within said unit, and annular means associated with the respective

ends of said supporting member for engaging at spaced intervals against the end faces of said brushing unit and overlapping the outer face only of the outer channel strip area of said brushing unit to a position above the plane of the holding wire and having elements intermediate the brushing strands thereof for clamping said brushing unit upon said supporting member.

7. An apparatus of the character described having in combination a brushing unit formed of a channel strip carrying brushing strands engaged around a holding wire within said channel strip and wound to spiral form, at least one supporting member engaged within said unit, annular means associated with the respective ends of said supporting member for engaging at spaced intervals against the end faces of said brushing unit and overlapping the outer face only of the outer channel strip area of said brushing unit to a position above the plane of the holding wire and having elements intermediate the brushing strands thereof for clamping said brushing unit upon said

supporting member, and means for mounting said supporting member upon a driving shaft.

8. An apparatus of the character described having in combination a brushing unit formed of a channel strip carrying brushing strands engaged around a holding wire within said channel strip and wound to spiral form, a tubular supporting member engaged within said unit, annular means associated with the respective ends of said supporting member for engaging at spaced intervals against the end faces of said brushing unit and overlapping the outer face only of the outer channel strip area of said brushing unit to a position above the plane of the holding wire and having elements intermediate the brushing strands thereof for clamping said brushing unit upon said supporting member, and means for mounting said supporting member upon a driving shaft and for clamping said supporting member against the end faces of the brushing unit.

DIETRICH F. O. WESEMAYER.
